(57) **CLAIM**

The ornamental design for an applicator head for taping machine as shown and described.

DESCRIPTION

FIG. 1 is an isometric view of an applicator head for taping machine showing the new design;

FIG. 2 is an enlarged view of area D of the applicator head for taping machine of FIG. 1;

FIG. 3 is a front view thereof; and

FIG. 4 is a right side view thereof.

FIG. 5 is a left side view thereof; and

FIG. 6 is a rear view thereof.

FIG. 7 is a top view thereof; and,

FIG. 8 is a bottom view thereof.

The broken line circles in the FIGS. 1 and 2 of the drawings illustrate the bounds of the enlarged view and form no part of the claimed design.

The broken lines in the drawings depict portions of the applicator head for taping machine that form no part of the claimed design.
